UNITED STATES PATENT OFFICE.

JOHN J. RONDERS, OF MONONGAH, WEST VIRGINIA.

RAILWAY SWITCH.

Application filed October 26, 1922, Serial No. 597,016.

To all whom it may concern:

Be it known that I, JOHN J. RONDERS, a citizen of the United States, residing at Monongah, in the county of Marion and State of West Virginia, have invented certain new and useful Improvements in Railway Switches, of which the following is a specification.

This invention relates to improvements in railway switches.

The primary object of the invention is to provide a railway switch in which the parts will be so constructed and arranged and so operated as to insure against wrecks such as result from displacement of the switch point or the frog.

Another object of the invention is to provide a novel construction of frog and means for mounting and operating the same which construction will be more substantial than those ordinarily employed and not as liable to become damaged through the impacts to which it is subjected.

Another object of the invention is to provide a novel form of switch point and a novel means for actuating the same, the point being so constructed and mounted and operated in such a manner as to insure against accidents through its disarrangement from any cause, such for example, as the dropping and dragging of a brake shoe or other part of a car passing over the switch.

In the accompanying drawings:

Figure 1 is a plan view of the switch embodying the invention, the point and frog being adjusted to position to provide for travel over the main track;

Fig. 2 is a vertical transverse sectional view taken substantially on the line 2—2 of Fig. 1 looking in the direction indicated by the arrows;

Fig. 3 is a group perspective view illustrating the frog and the mounting therefor;

Fig. 4 is a detail vertical transverse sectional view on the line 4—4 of Fig. 1 looking in the direction indicated by the arrows and showing the switch points in position for travel of the train over the main track;

Fig. 5 is a similar view illustrating the points in position for travel of the train over the side track;

Fig. 6 is a sectional perspective view illustrating one of the switch points, the

actuating means therefor, and the main track rail with which it coacts;

Fig. 7 is a detail transverse sectional view substantially on the line 7—7 of Fig. 1 looking in the direction indicated by the arrows;

Fig. 8 is a view similar to Fig. 3 illustrating a modified form of frog;

Fig. 9 is a plan view illustrating a further modified form of frog;

Fig. 10 is a transverse sectional view on the line 10—10 of Fig. 9;

Fig. 11 is a view similar to Fig. 4 illustrating a modified form of switch point and operating means therefor;

Fig. 12 is a view similar to Fig. 9 illustrating a modification of the invention.

In the drawings the main track rails are indicated, one by the numeral 1 and the other by the numeral 2, and the siding rails 3 one by the numeral 3 and the other by the numeral 4, the rails being mounted upon the usual ties 5.

In that form of the invention shown in Fig. 1 and the associated figures of the drawings, the base or foundation for the frog which is indicated in general by the numeral 6, is mounted at the cross over between the rails 2 and 3 and comprises a body 7 which is spiked to the ties in the usual manner and is provided at one end with a wedge-shaped boss 8 which is seated between the converging ends of sections of the rails 2 and 3 and bolted thereto. The body is provided at its upper side with channels 9 and 10 located at opposite sides of the boss 8 for the passage of the wheel flanges and having walls alining respectively with the rails 2 and 3. The said body 7 is likewise provided in its upper side with a transversely extending recess 11 opening through the opposite side faces of the body and slidably receiving the frog which is indicated in general by the numeral 12. The said frog comprises a body 13 having a central wedge-shaped portion 14 constituting the frog proper, the upper side of the body being formed with channels 15 and 16 located at opposite sides of the frog portion 14 and being designed to be brought into alinement respectively with the channels 9 and 10 upon shifting adjustment of the frog in the recess 11. In order that the frog 12 may be retained in place upon its supporting base 6, the base is formed in the bottom wall of the recess 11 with a trans-

verse slot 17, and the body 13 of the frog is formed upon its under side with a boss 18 which slidably fits in the said slot 17. The body 7 is likewise formed with a longitudinally extending horizontal slot 19 which intersects the slot 17, and a key plate 20 is fitted through the slot 19 and extends also through a slot 21 formed transversely in the boss 18. In this manner the frog 12 is retained in place within the recess and yet may have transverse sliding movement so as to bring its channels 15 or 16 into selective alinement with the respective channels 9 and 10. The body 7 at its end opposite its end which is provided with the boss 8, is formed with a recess 22 opening into the recess 11, and the side walls of this recess 22 occupy the same plane as the guiding side walls of the channels 9 and 10. At the opposite sides of the recess 22, the body 7 is recessed as at 23 to accommodate the connected ends of the other sections of the rails 2 and 3. In order that the frog may be shifted across its base to position the frog proper for travelling of the train over the main track or the siding, the body 13 is provided at one end with an ear 24 having an opening 25 in which is engaged the bent up end 26 of a rod 27 slidably mounted as at 28 upon one of the ties 5, this rod being adapted to be shifted under conditions and by means to be presently explained.

The switch point, in this form of the invention, is indicated in general by the numeral 29, and the same may, if desired, be formed from a length of ordinary rail or it may be initially formed of the required shape from other stock material. In any event the point will comprise a head 30 corresponding in general form to a section of an ordinary rail head, a web 31, and a base flange 32. As distinguished from the ordinary switch point which is swiveled at its butt-end to the main or siding rail, as the case may be, and is adapted to be swung toward and away from the companion rail, the point embodying the invention is hinged at the edge of its base flange as at 33, to the ties or any other base structure which it may be found advisable to employ, and the point is adapted to be moved upon its hinges so as to occupy a position resting against the side of the rail or a position tilted away from the rail to permit of passage of the wheel flanges. In order that a smooth and unobstructed surface may be provided at the treads or heads of the rails where the switch point meets the companion rail, the said companion rail preferably has one side of its head formed with a shallow recess 34 into which the tongue of the point is adapted to seat when the point is swung up to position beside the rail. This recess is as stated, shallow, so that even when the point is away from the rail the wheel flanges may pass

the recess without any battering of the rail or injury to the wheels. At the same time when the tongue of the point is seated in the recess, the outer or guiding side of the head of the point will be flush and even with the corresponding side of the head of the rail and there will be no likelihood of damage to the point when the wheels pass over the same. In the form of the invention shown most clearly in Figs. 1, 4, 5 75 and 6 of the drawings, the operating means for the switch points comprises a bar 35 which is pivoted at one end as at 36 to the under side of a plate 37 secured upon the ties 5, the bar extending between two adjacent ones of the ties and beneath the rails and the switch points associated therewith. The base flange of each rail is cut away at a suitable point as indicated by the numeral 38, this cut away portion being in the side of the flange next adjacent the switch point, and the bar 35 is formed with an overhanging lip 39 which is adapted to ride over the upper side of the base flange of the rail in the movement of the bar 35 about its pivot. The bar 35 is also provided with a similar lip 40 which engages over the base flange 32 of the switch point 29. Also the bar is formed between the lips 39 and 40 with an upstanding tongue 41, the upper end of which may be slightly deflected laterally toward the lip 40 as indicated by the numeral 42 to ride against the inner side of the web 31 of the switch tongue point 29. Of course, the bar 35 will be provided with two sets of the elements 39, 40 and 41 for coaction with the two switch points which extend above the bar. The tongue 41 is accommodated within the cutout portion 38 of the base flange of the rail with which the respective switch point coats, and it will be understood that when the bar is swung about its pivot in either direction, one of the lips 40 thereon will ride against the respective switch point and swing the same about its hinges to upright position against the companion rail as shown clearly at the left of Fig. 4 of the drawings, the tongue 41 associated with the other switch point riding against the same to tilt the point about its hinges to position spaced from the companion rail as shown at the right in said Fig. 4. A swinging of the bar 35 about its pivot in the opposite direction will effect a reverse operation of the two switch points as clearly shown in Fig. 5. 110

In order that the bar 35 may be actuated a switch stand 43 is provided and comprises a suitable mounting 45 having a finger 46 extending below its pivot and working through an eye 47 swiveled to the end of the bar 35. In order that when the lever 45 is thrown to adjust the switch points, the frog 12 will be correspondingly automatically adjusted, a rod 48 is connected at one end to the bar 35 and at its other end to one arm of 115 120 125 130

an angle lever 49 mounted, as at 50, upon one of the ties. The other arm of this lever has a pin and slot connection 51 with the sliding rod 27 and it will be evident by reference to 5 Fig. 1 of the drawings and the full and dotted line positions shown therein, that movement of the bar 35 to throw the switch points for travel of the train upon the main track, will result in a corresponding adjustment 10 of the frog 12, the frog being likewise adjusted when the bar 35 is moved to throw the switch points for travel of the train upon the siding.

Fig. 8 of the drawings illustrates a modified form of frog and in this figure the base or foundation of the frog is indicated by the numeral 53 and the frog is indicated by the numeral 54. The body 53 is similar in its construction to the body 7 of the frog 20 shown in Fig. 3 of the drawings, and the frog 54 which is mounted upon the body or foundations 53, is similar to the frog 12. In this modified structure, however, the body 53 is formed at opposite sides of the recess 25 55 which corresponds to the recess 11, with sockets 56 in which are fitted the right angularly turned ends 57 of a key plate 58 which plate extends across the respective end of the recess 55 and through a slot 59 formed 30 in the respective end of the frog 54, it being understood that a pair of the key plates are provided and that they are arranged at opposite sides of the body 53. Pins 60 or other suitable fastening elements may be fitted 35 downwardly through openings 61 in the body 53 and through registering openings 62 formed in the ends 57 of the key plates so as to retain the plates in place.

In the form of the invention shown in 40 Figs. 9 and 10 of the drawings the base or foundation for the frog is indicated by the numeral 63 and is formed in its upper side with a recess 64 in which is disposed the frog proper indicated in general by the numeral 45 65. The said frog 65 comprises a substantially wedge-shaped body 66 which is freely shiftably mounted in the recess 64 transversely thereof, and a key plate 67 is fitted transversely through a slot 68 formed in the 50 body 66 and secured by rivets or any other suitable fastening elements 69. The ends of this plate project slidably through slots 70 formed in the opposite side walls of the recess 64, and one end of the key plate is 55 provided with an opening 71 to accommodate an actuating rod corresponding to the rod 27.

In that form of the invention shown in 60 Fig. 11 of the drawings, the switch points which are indicated by the numeral 72 are hinged at their base flanges as indicated by the numeral 73, and a bar 74 is slidably mounted beneath the rails and switch points,

in suitable guides 75, and is provided with upstanding arms 76 pivotally connected as 65 at 77, to the said switch points. An operating lever 78 is pivotally mounted as at 79 and provided with an arm 80 which works through one end of the bar 74, and it will be evident by reference to the said figure 70 that when the lever is rocked in one direction, one switch point will be thrown to position beside its respective rail and the other point away from its respective rail, and when the lever is swung in the opposite direction the position of the switch point will 75 be reversed.

In the form of the invention shown in Fig. 12 of the drawings the frog is similar in construction to that illustrated in Fig. 80 9, except that in this case it may be made by a combination of suitable pieces of ordinary rail and is disposed upon a metallic base plate 81, the structure being secured in place by any suitable means 82.

It will be understood that while several forms of the frog and its associated parts and several forms of the switch point and its associated parts have been illustrated and described, such illustration and description 90 is to be taken merely as representing possible embodiments of the invention, the principles of the invention being capable of embodiment in various other structures if found desirable.

Having thus described the invention, what is claimed as new is:

1. In a railroad switch, the combination with main and siding rails, of a supporting base arranged at the cross over of two of 100 said rails and having a transverse recess in its upper side and having guiding faces alining with the respective rails, a frog shiftable in the recess and having channels for alinement with the respective rails, a 105 key engaging the frog and the base to retain the frog in the recess in the base, and means for shifting the frog.

2. In a railroad switch, the combination with main and siding rails, of a supporting 110 base arranged at the cross over of two of said rails and having channels in the upper side alining with the respective rails, the said base having a recess extending transversely thereof into which the channels 115 open, and a slot in the bottom of the recess, a frog shiftably mounted in the recess and having channels for registration selectively with the first-mentioned channels, a boss depending from the frog into the slot in the base, a key plate engaging the base and said boss to retain the frog in the recess in the base, and means for shifting the frog.

In testimony whereof I affix my signature.

JOHN J. RONDERS.
